JOHN J. TATUM.

END SILL FOR FLAT CARS.
APPLICATION FILED FEB. 17, 1916.

1,210,117.

Patented Dec. 26, 1916.

Inventor,
J. J. Tatum,
By *J. J. Tatum, Atty.*

UNITED STATES PATENT OFFICE.

JOHN J. TATUM, OF BALTIMORE, MARYLAND.

END SILL FOR FLAT-CARS.

1,210,117.

Specification of Letters Patent. Patented Dec. 26, 1916.

Application filed February 17, 1916. Serial No. 78,856.

To all whom it may concern:

Be it known that I, JOHN J. TATUM, a citizen of the United States, residing at Baltimore, Maryland, have invented a certain new and useful Improvement in End Sills for Flat-Cars, of which the following is a full, clear, and exact description, such as will enable others skilled in the art to which it appertains to make and use the same, reference being had to the accompanying drawings, forming part of this specification.

My invention relates generally to flat cars and more particularly to an end sill therefor, the principal object of my invention being to construct a flat car end sill with a portion which projects a substantial distance above the floor level of the car so that the material or objects forming the load of the car may be braced or have bearing against this upward projection so as to prevent lengthwise shifting movement on said car as the latter is buffed or pulled with sudden jerking movement during switching operations.

It will be understood that the top surface of the flooring of the ordinary flat car is flush with the top of the end sill and to anchor and prevent shifting movement of the load of the car it is customary to nail blocks of wood to the floor of the car. Such practice results in damage to the flooring, thereby necessitating frequent repairs and I propose to overcome this objection by forming on the end sill a permanent flange or upward projection which serves as a brace or bearing for the material or objects placed on the car.

A further object of my invention is to combine with the end sill a hinged plate or apron which is adapted to occupy a flat position upon the car flooring when long objects or material form the lading of the car, to occupy a vertical position when it is desired to provide the car with a closed end, and to be swung outward so as to occupy a horizontal position and span the space between the end sills of two cars when the cars are utilized for hauling dirt, sand, cinders or the like.

A further object of my invention is to provide a flat car end sill with openings or pockets which are adapted to receive vertically disposed stakes, and which latter can be used when it is desired to have a taller support or bearing than is provided by the

upwardly projecting portion of the end sill, thus making it possible to take care of a load which extends to a considerable height above the surface of the car floor.

With the foregoing and other objects in view, my invention consists in certain novel features of construction and arrangement of parts, hereinafter more fully described, claimed and illustrated in the accompanying drawings, in which—

Figure 1 is a plan view of the end portion of a flat car, the same being equipped with an end sill of my improved construction. Fig. 2 is a front elevational view of the end sill. Fig. 3 is an enlarged cross sectional view taken approximately on the line 3—3 of Fig. 2.

As illustrated in the drawings, my improved end sill is in the form of an elongated tubular member of cast metal, preferably square or box-shape in cross section and comprises a front wall 10, rear wall 11, top 12 and bottom 13. Formed at the center of the body of the sill is an opening 14 for the draw-bar and the sill to the sides of this opening is extended downward as designated by 15 and formed integral with the undersides of these downwardly extending portions are brackets 15, which serve as supports for the carry iron (not shown). Formed in the front wall 10 near the ends of the sill are the usual push pole pockets 16. Formed integral with the top of the sill and preferably in alignment with the rear wall 11 thereof is an upwardly projecting flange 17 which extends substantially the entire length of the sill. Formed through the top plate 12 are apertures 18 which are adapted to receive stakes and formed integral with the top plate 12 around these openings are depending flanges 19 which serve as bearings for said stakes.

Formed integral with the top of the end sill thus constructed and preferably immediately adjacent to the flange 17 are perforated lugs 20 to which are hinged lugs 21, the same being formed on or fixed to the edge of a metal plate or apron 22. When comparatively long objects such as track rails, wire supporting poles, or the like, are utilized with the lading of the car, equipped with my improved end sills, the aprons 22 are folded inwardly so that they lie flat on the end portions of the car flooring. Where comparatively short and heavy objects, such

as stone, heavy castings, ties, or the like, form the lading of the car, the aprons are swung into vertical positions and bear against stakes, such as 24, the lower ends of which are inserted through the openings 18.

5. The heavy objects forming the load of the car are positioned on the floor so that they bear directly against the flange 17, or if desired, bearing blocks of wood or the like 10 can be interposed between the objects and said flange. Thus the load of the car is firmly held and practically anchored against lengthwise shifting movement upon said car by reason of sudden jerks produced by 15 the buffing and pulling movement imparted to the car as the same is switched or moved in transportation.

The apron 22 when occupying a vertical position and bearing against stakes 24, forms 20 an end wall which is effective in holding loads which rise to a considerable height above the car flooring.

When cars equipped with my improved 25 end sills are utilized for hauling dirt, the aprons are swung outward so as to occupy horizontal planes and span the space between an adjacent pair of the end sills, and thus, said aprons provide guides and supports for the plow which is drawn from one 30 end of the train to the other for the purpose of discharging the dirt and said aprons also prevent the dirt or material from falling between the ends of the cars.

An end sill of my improved construction 35 is comparatively simple, can be easily and cheaply manufactured, provides efficient means for holding the load of the car against lengthwise shifting movement upon the floor of said car, and the apron combined with the end sill can be utilized as 40 an end wall or for a plate or flooring between an adjacent pair of the end sills.

It will be readily understood that minor 45 changes in the size, form and construction of the various parts of my improved end sill can be made and substituted for those herein shown and described, without departing from the spirit of my invention, the scope of which is set forth in the appended claims.

50. I claim:

1. A cast metal end sill for flat cars, an upwardly projecting load retaining member formed on said sill, said sill being provided with a series of stake pockets and an 55 apron hinged to the top of said sill between

the load retaining member and said stake pockets.

2. A cast metal end sill for flat cars having an integral upwardly projecting load retaining member, said sill being provided 60 with a series of stake pockets and an apron hinged to the top of said sill between the load retaining member and said stake pockets.

3. The combination with a flat car under-frame and flooring, of an end sill fixed to said underframe and provided with a portion which extends a substantial distance above the surface of the flooring, there being a series of stake pockets formed in said 70 end sill and an apron hinged to the top of said sill between the upwardly projecting portion and the stake pockets.

4. The combination with a flat car under-frame and its flooring, of an end sill fixed 75 to said underframe, a flange integral with the top of said end sill, which flange projects a substantial distance above the surface of the flooring, there being a series of stake pockets formed in said end sill and a 80 metal apron hinged to the top of the sill between the flange and the series of stake pockets.

5. A cast metal car end sill provided with a longitudinally disposed row of stake pockets, an upwardly projecting load retaining member formed on said sill adjacent to said 85 pockets, and an apron hinged to said sill between said pockets and load retaining member.

6. A cast metal car end sill provided in its upper portion with a longitudinally disposed row of stake pockets, an upwardly projecting load retaining member formed integral with the upper rear corner of said 95 sill, lugs on said sill between the row of stake pockets and the load retaining member, and an apron hinged to said lugs.

7. The combination with a car end sill provided with a longitudinally disposed 100 row of stake pockets, of an apron hinged to the top of said sill immediately to one side of the row of stake pockets therein.

In testimony whereof I hereunto affix my signature in the presence of two witnesses, this Feb. 12 day of 1916.

JOHN J. TATUM.

Witnesses:

E. C. CHANEY,
SIMON GREENEBAUM.
